The ornamental design for a carrying bag, as shown and described.

DESCRIPTION

FIG. 1 is a perspective view of the carrying bag showing the front side of the bag and the right side thereof;

FIG. 2 is a front view of the carrying bag in the closed position;

FIG. 3 is a rear view of the carrying bag in the closed position;

FIG. 4 is a right side view of the carrying bag in the closed position;

FIG. 5 is a left side view of the carrying bag in the closed position;

FIG. 6 is a top view of the carrying bag in the closed position;

FIG. 7 is a perspective view of the carrying bag in the laid open position, this view showing the inner surface of the bag;

FIG. 8 is a plan view of the carrying bag in the laid open position, this view showing the outer surface of the bag;

FIG. 9 is a plan view of the carrying bag in the laid open position, this view showing said inner surface;

FIG. 10 is a longitudinal edge view of the carrying bag in the laid open position;

FIG. 11 is an end edge view of the carrying bag taken from the left end of FIG. 9; and,

FIG. 12 is an end edge view of the carrying bag taken from the right end of FIG. 9.
